UNITED STATES PATENT OFFICE

155,778

DESIGN FOR A RAINBOOT

James R. Carr, San Carlos, Calif.

Application February 15, 1949, Serial No. 882

Term of patent 14 years

(Cl. D7—4)

To all whom it may concern:

Be it known that I, James R. Carr, a citizen of the United States, residing at San Carlos, in the county of San Mateo and State of California, have invented a new, original, and ornamental Design for Rainboot, of which the following is a specification, reference being had to the accompanying drawing, forming part thereof.

Fig. 1 is a side elevational view of the rainboot, showing my new design.

Fig. 2 is a bottom plan view of the rainboot shown in Fig. 1.

Fig. 3 is a top plan view of the rainboot shown in Fig. 1.

Fig. 4 is a rear end elevational view of the rainboot shown in Fig. 1.

Fig. 5 is a front elevational view of the rainboot

shown in Fig. 1 with the free flowing straps omitted for convenience of illustration.

I claim:

The ornamental design for a rainboot, as shown and described.

JAMES R. CARR.
